UNITED STATES PATENT OFFICE.

WILLIAM E. SPARKS, OF NEW HAVEN, CONNECTICUT, ASSIGNOR TO THE NASHUA LOCK COMPANY, OF NASHUA, NEW HAMPSHIRE.

NAME AND DROP-LETTER PLATE.

SPECIFICATION forming part of Letters Patent No. 339,819, dated April 13, 1886.

Application filed September 30, 1884. Serial No. 144,340. (No model.)

To all whom it may concern:

Be it known that I, WILLIAM E. SPARKS, a citizen of the United States, residing at New Haven, in the county of New Haven and State 5 of Connecticut, have invented certain new and useful Improvements in Name and Drop-Letter Plates, of which the following is a specification.

My invention relates to improvements in 10 drop-letter plates of the class having a stationary back plate and connected thereto by a movable lid or cover.

In the accompanying sheet of drawings, 15 Figure 1 is a front elevation of my improved name and drop-letter plate. Fig. 2 is a like view thereof with the letter-mortise uncovered. Fig. 3 is a rear elevation of the same.

My improved name and drop letter plate consists, essentially, of two parts—a back 20 plate, A, and a cover-plate, B. The back plate, A, is provided with an opening or letter-mortise, *a*, for the insertion of letters, papers, &c., which extend near to the lower right-hand corner thereof, a curved opening, 25 *b*, near its right-hand edge, and at the left-hand side of the plate *a*, near its edge, a circular perforation, *e*. On the face of the cover-plate B any desired name is engraved or otherwise placed thereon—as, for instance, the name 30 of the person occupying the place where the plate is to be used. On the rear of the cover-plate there is a projection, *c*, and a pivotal lug or pin, *d*, of sufficient length to extend through the openings *b* and *e* in the back 35 plate. Pins *ff* in the projection *c* and pivotal pin *d* at the rear of the back plate hold the parts A and B together. When the back and cover plates are thus secured together, the cover-plate will turn edgewise on its axis, 40 formed by the pin *d* and the perforation *e*, so that one end of said cover-plate may be lifted until its upward movement is limited by means of the projection *c* reaching the upper end of the curved opening *b*, as shown in Fig. 2, 45 and thereby uncover the letter-mortise *a*. When the cover-plate is released, it will of its own weight fall to its former position, as

shown in Figs. 1 and 3, the downward movement of the cover being limited by the projection *c* reaching the lower end of the curved 50 opening *b*.

The screw-holes *g g* are for the reception of fastening-screws to secure the device upon a door or other place where it is to be used.

I am aware that a prior patent shows a letter-box having a covering-plate pivoted so as to swing edgewise instead of sidewise, the back plate of which has a horizontal shoulder against which the lower edge of the covering-plate rests when it covers the letter-mortise. 55 The cover-plate of this prior device is fastened to the back plate only at one end, and that by means of its axle. Such a device is hereby disclaimed. 60

By my improved construction the cover-plate is so fastened at both ends as to always 65 be held closely to the back plate, while the stop is concealed from view, thereby enabling the covering-plate to occupy a central position on the back plate, as shown in Fig. 1, 70 and produce a neat finish having the appearance of an ordinary door-plate.

I claim as my invention—

1. The herein described drop-letter plate, 75 consisting of the back plate having a letter-mortise and the curved opening *b*, and the cover-plate pivoted thereto near one end, so as to turn edgewise, and having the projection *c*, working in the curved opening *b*, to serve as a stop, all substantially as described, and 80 for the purpose specified.

2. The herein-described drop-letter plate, 85 consisting of the back plate having a letter-mortise, and the cover-plate pivoted near one end to said back plate, so as to swing edgewise, said plates being connected at the end which is opposite the pivot by means of a projection on one plate extending through a slot in the other plate, substantially as described, and for the purpose specified.

WILLIAM E. SPARKS.
